KEYBOARD OR THE LIKE

Paul B. Reinhold, 635 Ridge Ave., Pittsburgh, Pa.

Filed Sept. 26, 1962, Ser. No. 71,858

Term of patent 14 years

(Cl. D33—3)

The single figure is an isometric view of a keyboard showing my new design.

The side not shown is like the side shown while the back is plain and unornamented.

I claim:

The ornamental design for a keyboard or the like, substantially as shown and described.
